(57) **CLAIM**

The ornamental design for a neck massager, as shown and described.

DESCRIPTION

FIG. 1 is a top-front perspective view of a neck massager according to the present invention;

FIG. 2 is a bottom-front perspective view thereof;

FIG. 3 is a top-rear perspective view thereof;

FIG. 4 is a bottom-rear perspective view thereof;

FIG. 5 is a front elevation view thereof;

FIG. 6 is a rear elevation view thereof;

FIG. 7 is a left side view thereof;

FIG. 8 is a right side view thereof;

FIG. 9 is a top plan view thereof; and,

FIG. 10 is a bottom plan view thereof.

The broken lines in the drawings are for the purpose of illustrating portions of the neck massager that form no part of the claimed design.

1 Claim, 10 Drawing Sheets
